COMBINED BOTTLE AND CLOSURE CAP

Robert Olifiers, Scarsdale, N. Y.

Application February 20, 1956, Serial No. 40,237

Term of patent 14 years

(Cl. D58—6)

Fig. 1 is a front elevational view of a combined bottle and closure cap embodying my new design;

Fig. 2 is a side elevational view thereof;

Fig. 3 is a front elevational view with the closure cap removed; and

Fig. 4 is a top plan view thereof.

The dominant feature of my design resides in the portions shown in full lines.

I claim:

The ornamental design for a combined bottle and closure cap, as shown and described.
